PORTABLE BRANDING DEVICE

Deane Carlisle Severance, Huntington Park, Calif.

Application January 14, 1950, Serial No. 138,544

2 Claims. (Cl. 219—30)

1

This invention relates to branding devices, and more particularly to a portable, electrically heated, manually operable branding device for hot branding initials, symbols, emblems, etc., from thin metal foil into a surface.

It is often desirable to mark for identification purposes articles of a personal nature, such as purses, billfolds, brief cases, luggage, key containers, etc., and collections of articles such as phonograph records and books of a library. Such identification marking obviously should be neat and attractive so as not to detract from the appearance of an article and in some cases may be employed to enhance the appearance of an article, as when the mark is composed of fanciful indicia and applied to a purse. Such indicia usually includes part of a name, initials of an owner, or may comprise a distinctive symbol or emblem.

Such an identification mark is sometimes applied to an article at the time of purchase. As other articles are obtained, identification indicia of the same kind as previously used may or may not be branded into the surface of the new article. In the case of books and phonograph records, it is extremely desirable for an owner to be able to uniformly mark such articles with his particular identification indicia. Prior branding devices for this purpose were expensive, rather cumbersome, and required a skilled operator for performing a branding operation carefully and skillfully without damage to an article.

The primary object of this invention is to design and provide a portable, manually operable branding device for conveniently and effectively hot branding metal foil into a surface.

Another object of this invention is to provide such a branding device which utilizes electrical heating means for heating branding indicia to proper temperature and which may be readily connected to any convenient standard electrical outlet.

A further object of this invention is to provide a novel, portable, electrically heated branding device which is so constructed and arranged as to readily permit interchange of brand indicia, symbols, or emblems.

Still another object of this invention is to provide an improved, portable, branding device wherein the brand indicia are automatically retracted into a guard portion for reducing danger of injury or fire hazard to a minimum when the branding device is not being employed in a branding operation.

A still further object of this invention is to

2

provide a novel portable branding device wherein electrical resistance heating means may be electrically connected so as to heat the branding head and brand indicia carried thereby only when the branding device is being employed in a branding operation.

Generally speaking, this invention contemplates a branding device capable of being employed with various types of thin metal foil wherein the device comprises a hollow hand-hold body having an open end which telescopically receives an upper extension on a guard member. The guard member includes a lower hollow guard portion of polygonal section which encloses therewithin a branding head of smaller cross-sectional plan but of corresponding polygonal section for non-rotatable and slidable accommodation within the lower guard portion. The head is connected to the hand-hold body by a central post and an elongated securing bolt so that downward movement of the body, when branding, moves the branding head including branding indicia downwardly into contact with a metal foil. Electrical resistance means is carried by the branding head for heating the branding indicia, the resistance means being conveniently connected to a source of electricity by a suitable connecting cord. The lower guard portion is provided with positioning and guide means for aligning metal foil with the branding indicia. The guard member is spring biased downwardly with respect to the hand-hold body so that the branding head will be automatically retracted within the lower guard portion when pressure is withdrawn from the hand-hold body.

Other objects and advantages of this invention will be readily apparent from the following description of the drawings.

In the drawings:

Fig. 1 is a sectional view of a branding device embodying this invention, the section being taken in a vertical plane bisecting the device.

Fig. 2 is a bottom view of the device shown in Fig. 1, and showing in diagrammatic lines the branding head located out of alignment with the lower guard portion for holding the branding head in position while changing branding indicia.

Fig. 3 is a fragmentary sectional view showing the branding head located with respect to the lower guard portion, as illustrated in diagrammatic lines in Fig. 2.

Fig. 4 is a partial sectional view showing the branding device in closed, operative branding position.

Fig. 5 is a sectional view of a different modification embodying this invention, the section being taken in a vertical plane bisecting the device.

Fig. 6 is a fragmentary sectional view of the modification shown in Fig. 5, illustrating separable electrical contacts in closed position when the branding device of Fig. 5 is pressed downwardly for a branding operation.

In Fig. 1, a portable branding device generally indicated at 10, embodies one modification of this invention which is adapted to be connected to an electrical source for constant heating of brand indicia for a branding operation.

The branding device 10 comprises an upper hollow, cylindrical, hand-hold body 11, provided with an end wall 12 closing its upper end and with a lower open end 13. The body 11 is preferably made of a suitable dielectric material which not only affords electrical insulation, but is also capable of resisting heat. Received within the open end 13 is a cylindrical upper extension 14 formed on a hollow guard member 15 of similar dielectric material, said upper extension 14 being adapted to reciprocally slide within the hollow body 11.

The guard member 15 is provided with a lower hollow guard portion 16 preferably of polygonal section, shown here as being rectangular. The lower guard portion is provided with an internal shoulder 17 spaced inwardly from the lower end of portion 16 for providing a stop or abutment against which edge margins of a branding head 18 may seat when the device is in inoperative extended position.

The branding head 18 is of smaller and corresponding polygonal section than the polygonal section of the lower guard portion 16 for non-rotatable and slidable accommodation within the guard portion. The branding head 18 includes an upstanding, central, elongated boss or projection 19 integrally formed therewith, said boss having a threaded axial bore 20 in its upper end for receiving an elongated assembly screw bolt 21. The bolt 21 extends through an axial bore 22 formed in a central post 23 which is seated against the inner surface of end wall 12 and the upper edge of the upstanding boss 19, said post passing through a central guide opening 24 formed in an end wall 25 which closes the upper end of extension 14 of the guard member 15. The bolt 21 connects the branding head 18 with the hollow hand-hold body 11 for movement therewith.

The guard member 15 is spring biased downwardly from the body 11 by a coil spring 26 encircling post 23 and having one end seated against end wall 12 and the other end seated against wall 25 of the extension 14. The spring thus urges the internal shoulder 17 on the guard portion against edge margins of the branding head. The cooperative relation of the shoulder and head, together with the spring, holds the device in proper assembled relation.

The branding head 18 includes a longitudinally extending dovetail groove 29 formed in its lower surface for removably receiving brand means or indicia 28. The brand indicia 28 may include selected symbols, emblems or letters for branding a selected mark into a surface of an article. Opposite end walls 30 of the lower polygonal guard portion 16 may be provided with aligned dovetail grooves 31 for guidably receiving and positioning a thin strip of metal foil 32 beneath the brand indicia. The metal foil employed may be gold, bronze, aluminum, or the like.

The branding head and indicia, which are

preferably made of heat conducting material, are electrically heated by means of a resistance coil 33 encircling the lower portion of the central boss 19 of head 18. Heat from the resistance coil

5 33 is readily transmitted through the branding head 18 to the brand indicia for burning metal foil 32 into a surface to be branded when the hand-hold body 11 and connected branding head are pressed downwardly. The resistance coil 33

10 is suitably electrically connected to one end of an attached cord 34 which may be plugged at its other end into a convenient source of electricity, said cord passing through a port 35 in body 11.

The selected brand indicia may be conveniently 15 interchanged by pressing the hollow hand-hold body 11 downwardly until the head 18 projects beyond the edge of the lower guard portion and then rotating the body so that the polygonal head 18 is rotated out of alignment with the lower 20 guard portion and diagonally seats on the bottom edge of the lower guard portion, as indicated in Figs. 2 and 3. Brand indicia may then be interchanged by withdrawing brand indicia from the end of the groove and inserting the other selected indicia. The branding head may then be rotated back to its normal aligned position and received within the guard portion 16.

Upon electrically connecting the resistance coil, 25 to a source of electricity, the brand indicia will 30 become heated by transfer of heat through the branding head from the resistance coil. When the brand indicia has reached a desired temperature, and the branding device has been positioned over a surface to be branded, the body 11 is manually 35 pressed downwardly for moving the brand indicia against the metal foil for hot branding the metal foil into said surface as shown in Fig. 4. As pressure is withdrawn the spring automatically 40 retracts the branding head into the guard portion until the head abuts the internal shoulder. The hot brand indicia is thus held in a protected position for minimizing fire hazard and for reducing possible damage to the indicia.

A removable material 36 such as wax or putty 45 may fill a counterbore 37 in wall 12 which receives the head of bolt 21 for minimizing transfer of heat from bolt 21, to the hand of the operator.

The modification of this invention shown in 50 Fig. 5, differs from the previous modification in that the resistance coil is carried as a unit upon a removable spool and in that the resistance coil is heated only when the hand-hold body is pressed downwardly for a branding operation.

The branding device generally indicated at 55 50 comprises an upper cylindrical, hollow hand-hold body 51 having an end wall 52 closing the upper end of said body and provided with a lower open end 53. An upper cylindrical hollow extension 54 of a guard member 55 is telescopically and slidably received within the open end 53 of the hand-hold body.

The guard member 55 includes a lower hollow 60 65 guard portion 56 of polygonal section as in the previous modification and is provided with an internal shoulder 57 spaced inwardly from the bottom edge of the guard portion 56.

A branding head 58 is non-rotatably and slidably accommodated within the lower guard portion 56 and is of corresponding polygonal section 70 as portion 56. The branding head 58 includes a central, upstanding portion 59 provided with a threaded central bore 60 in its upper end for threaded connection to an elongated assembly screw bolt 61. The screw bolt 61 extends through a central post 62 which is axially positioned by

means of a central aligning port 63 in an upper end wall 64 of the extension 54. The lower end of central post 62 is preferably seated against the upper end of portion 59 and adjacent end portions of a removable spool 65 carrying electrical resistance means 66 for holding the spool in assembled relationship with the head. The upper end of post 62 is provided with an axial recess 67 for receiving therewithin a depending internal central boss 68 formed on end wall 52 of the hand-hold body, said recess providing a shoulder 69 for spacing the upper edge of the post from the bottom surface of end wall 52. The upper end of post 62 is provided with an annular flange 70 affording a seat for one end of a coil spring 71, the other end of said spring being seated against the end wall 64 of the extension 54 of the guard member. The coil spring 71 encircles the post 62 and serves to spring-bias the guard member 55 downwardly from the body 51.

As in the previous modification, the branding head 58 includes a longitudinally extending dovetail groove 72 for removably holding brand indicia 73. The brand indicia 73 is heated by transfer of heat through the branding head from the resistance means carried on the spool 65 and for that purpose the branding head is preferably made of a metal material which readily conducts heat without losing its strength or form.

Means for electrically connecting the resistance coil 66 with an electrical source includes contact elements 74 and 75 normally held out of electrical contact by the action of the spring 71 in biasing the guard member 55 downwardly from the body 51. The contact element 74 may be connected by lead 76 to one end of the resistance coil 66 and is mounted on the upper surface of the end wall 64 of the extension, said wall 64 being provided with a port 77 through which the lead 76 extends. The contact element 74 may be curved slightly inwardly for receiving and for providing positive sliding electrical contact with the opposed end of contact element 75 which extends downwardly from the closed end of the body 51.

The contact element 75 includes a transverse plate portion which may be provided with a port for receiving boss 68. The plate portion is secured between the flange 70 of the post 62 and the end wall 52. The element 75 extends to the opposite side of the body 51 to provide a biased electric terminal 78 positioned opposite a port 79 in the wall of the body 51.

The other end of the resistance coil 66 is connected to a lead 80 which extends through an aperture 81 in the end wall 64 of the guard member for securement to the wall of the body 51 adjacent port 79. The end of lead 80 is provided with a terminal 82 positioned opposite terminal 78 and arranged to be contacted by spaced male elements 83 of a plug 84 on one end of an electric cord 85, the other end of which may be suitably connected to a standard electric outlet. The port 79 may be provided with a plug 86 of dielectric material receiving male elements 83.

As in the previous modification, the lower guard portion 56 is provided with aligned dovetail grooves 86 in the end walls of said portion for positioning and aligning a thin strip of metal foil beneath the branding indicia 73.

In operation of the device shown in Fig. 5, it will be apparent that when the branding device is not being used the spring 71 biases the body and the guard member into extended position and the contact elements 74 and 75 are separated and held out of electrical contact. When brand-

ing, downward pressure upon the hand-hold body 51 moves the contact element 75 into electrical contact with the contact element 74 for providing a closed circuit for heating the resistance coil 66. At the same time, the brand indicia is moved downwardly into contact with the metal foil and as the indicia is heated, the metal foil is hot branded into the surface of the article to be branded.

I will be readily apparent that when the branding operation is completed, as soon as the pressure is withdrawn from the body 51, the spring biases the body and guard member into extended position, separating the contact elements 74 and 75 out of electrical contact and retracting the hot branding indicia into the lower guard portion 56.

It will thus be readily apparent that a portable branding device has been provided with which any suitable metal foil, such as gold, aluminum, bronze, and other like materials, may be conveniently and readily hot branded into the surface of an article to be marked.

The branding indicia indicated in Fig. 2 as being a set of initials, may be easily changed by removing the indicia from the dovetail groove in the branding head and inserting other selected branding indicia after the head has been positioned as in Fig. 3. The metal foil employed is readily positioned and aligned for the branding operation because the polygonal shape of the lower guard portion together with the non-rotatable branding head permits accurate alignment of the branding device so that the metal foil will be branded in the selected position on the article being branded.

The provision of a hollow guard member within which the hot branding head and brand indicia are automatically retracted when the branding operation is completed affords a means for not only reducing the danger of fire hazard to a minimum, but also protects the indicia from damage and deformation when the branding device is not in use.

It will be understood that while the branding device is described in connection with branding of metal foil, obviously the device may be used for permanently burning a selected mark or indicia into a surface without using metal foil.

Other modifications and changes may be made in the embodiment of the invention described above, and all such changes coming within the scope of the appended claims are embraced thereby.

I claim:

1. In a hand operated portable device for hot branding metal foil into a surface, comprising: a hollow cylindrical hand hold body made of dielectric material and provided with an upper end wall and an open lower end; a hollow guard member of dielectric material provided with an upper tubular extension telescopically received within the lower open end of the hand hold body and with a lower guard portion of polygonal section; an internal downwardly facing shoulder between said guard portion and the extension; a central downwardly extending post secured to said upper end wall and extending into said extension; a branding head carried by the lower end of said post, said head being polygonal in plan to non-rotatably and slidably fit within said guard portion, peripheral margins of said head being adapted to seat on said shoulder for holding said hand hold body and guard member in assembled relation; a spring seat carried by the upper end of said extension; spring means compressed between

the spring seat and the upper end wall of the hand hold body for biasing the guard member downwardly to cover the branding head and to cause said head to seat on said shoulder; resistance means within the guard member and adjacent to the branding head; dovetail groove means extending across the bottom face of the branding head for reception of brand means; means including opposed aligned slots in the bottom margins of the lower guard portion for holding strip metal foil in alignment with said brand means while said head is retracted in normal assembled relation; said polygonal branding head being movable beyond the edge of the lower guard portion by downward pressure applied to the hand hold body for positioning said head on said edge by rotation of said hand hold body for interchanging the brand means.

2. In a hand operated portable device for hot branding metal foil into a surface, comprising: a hollow cylindrical hand hold body made of dielectric material and provided with an upper end wall and an open lower end; a hollow guard member of dielectric material provided with an upper tubular extension telescopically received within the lower open end of the hand hold body and with a lower guard portion of polygonal section; an internal downwardly facing shoulder between said guard portion and the extension; a central downwardly extending port secured to said hand hold body and extending into said extension; a branding head carried by the lower end of said post, said hand being polygonal in plan to non-rotatably and slidably fit within said guard por-

tion, peripheral margins of said head being adapted to seat on said shoulder for holding said hand hold body and guard member in assembled relation; a spring seat carried by the upper end of said extension; spring means compressed between the spring seat and the upper end wall of the hand hold body for biasing the guard member downwardly to cover the branding head and to cause said head to seat on said shoulder; resistance means within the guard member and adjacent to the branding head; dovetail groove means extending across the bottom face of the branding head for reception of brand means; and means including opposed aligned slots in the bottom margins of the lower guard portion for holding strip metal foil in alignment with said brand means while said head is retracted in normal assembled relation.

DEANE CARLISLE SEVERANCE.
